TELEVISION STAND

Claude M. Boissicat, 870 E. El Camino,
Mountain View, Calif. 94040

Filed Aug. 21, 1969, Ser. No. 18,782

Term of patent 14 years

Int. Cl. D6—01

U.S. Cl. D33—3

Fig. 1

Fig. 2

Fig. 3

Fig. 4

Fig. 5

FIG. 1 is a perspective view, taken from the right front, of a television stand showing my design;

FIG. 2 is a top view thereof;

FIG. 3 is a bottom view thereof taken along line 3—3 of FIG. 1;

FIG. 4 is a side elevational view thereof, the side opposite being a mirror image thereof; and

FIG. 5 is a rear view thereof.

I claim:

The ornamental design for a television stand, as shown.
